UNITED STATES PATENT OFFICE.

GEORGE WILLIAM SHAILER, OF WELLINGTON, NEW ZEALAND, ASSIGNOR
OF ONE-FOURTH TO MAURICE COHEN, OF SAME PLACE.

FASTENER FOR BAGS, MAIL-BAGS, &c.

SPECIFICATION forming part of Letters Patent No. 599,113, dated February 15, 1898.

Application filed May 14, 1897. Serial No. 636,560. (No model.)

To all whom it may concern:

Be it known that I, GEORGE WILLIAM SHAILER, a subject of the Queen of Great Britain, residing at 54 Lambton Quay, in the city 5 of Wellington, in the Colony of New Zealand, have invented an Improved Fastener for Bags, Mail-Bags, and other Receptacles; and I do hereby declare that the following is a full, clear, and exact description of the invention.

10 This invention has reference to fasteners used for closing the mouths of bags, securing the lids of receptacles, and for similar purposes, and is more especially advantageous for use upon mail-bags or receptacles which are 15 sealed after being closed, as a security against their contents being tampered with; and the object of the invention is to provide a durable, secure, inexpensive, and handy fastener which may be readily, rapidly, and easily ad- 20 justed upon or removed from a bag or other receptacle, and one which may be adjusted to fit articles of different sizes.

To the present time it has been the custom to fasten mail-bags with a string or cord and 25 affix the seal upon the string and bag, with the result that it was necessary to renew the string each time the bag was reclosed. A loss of time and expenditure of labor were thus entailed, which are overcome by my invention. 30 Further, the seal was frequently broken, owing to its being affixed to a flexible material which is subjected to considerable rough usage in transit from place to place.

In carrying out the object of the invention 35 I make a band preferably of band-steel or of hardened brass where it is desired to resist the effect of moisture. A piece of strong clock-spring is admirably suitable for the band, one end of which has a joint to receive 40 a lever, and near the other end a loop or loops is or are provided to receive a hook formed upon the said lever. In securing the bag a band is passed around the mouth in the same position as the string at present in use, and 45 a loop is slipped within the hook of the lever, which is then brought over to draw the parts close around the bag. Teeth upon the lever then engage with a catch on or in the band, and around or near this catch is provided a 50 boss or pad of material to which sealing-wax

will adhere, and such substances as vulcanite fiber, wood, and the like will be found suitable for the purpose, or it may be made of metal perforated with tapering holes, into which the wax may be run from the back, so 55 that the wax of the seal will adhere to the wax in the perforations. This said boss or pad is so shaped that it will protect the edges of the seal and will act as the capsule ordinarily used to protect the seal, and may be made of 60 any suitable material, such as cast metal, or stamped out of sheet metal. The band may be adjusted by hooking the lever into any one of the loops upon the band and engaging the hook upon the catch as required. 65

The fastener is applicable for use upon bags other than mail-bags and is intended to replace string or cord wherever used for tying up the mouths of bags, the lids of hampers, and the like. It may further be made in precious metals and ornamented for wear as a securely-fastening bracelet. 70

In order that the invention may be most easily understood, a description will now be given, while making reference to the accompanying drawings, whereon similar letters of reference indicate corresponding parts. 75

Figure 1 is a view of the fastener clasped upon and closing the mouth of a mail-bag. Fig. 2 is a view of the fastener opened out 80 ready to be placed around a bag or upon a receptacle. Fig. 3 is a view showing the first operation when closing the fastener. Fig. 4 is a view of the fastener when closed. Fig. 5 is a view of the loops or bars for adjusting 85 the size of the fastener. Fig. 6 is a section of the catch and pad to which the seal is affixed.

In describing the invention as applied to a mail-bag the fastener is opened, as shown on 90 Fig. 2, where the spring-band *a* is extended to receive the mouth of the bag *b*, Fig. 1, which said band is then allowed to close around the bag or is made to do so by the operator. The hook *c* is then made to engage 95 upon one of the loops or bars *d*, as shown on Fig. 3. The lever *f*, which is jointed to the elbow *g*, is then carried around until it reaches the position shown on Fig. 4, where one of the teeth *f'* of the lever engages upon the lug 100

h' of the catch *h* and where the size of the space inclosed by the band *a* has been considerably reduced to close upon the bag. The lever *f* is held within the catch *h* by the elasticity of the spring-band *a*. A seal may now be affixed upon the pad or boss *h*, which is grooved to admit the end of lever *f*, and recessed, as shown in the section Fig. 6. When made of metal, this said pad or boss is preferably perforated with tapering holes *h*⁴, which being filled with wax from the back will provide surfaces of wax upon the front, to which the wax used for the seal will adhere. The lever may be released by passing a pointed wire onto the holes *h*², Fig. 1, beneath the same and prizing the lever upward until it is free.

When used as a bracelet, the hook *c* is closed, so that the lever is permanently jointed upon a loop or bar *d*, one only of which is necessary, so that when the bracelet is open it will appear as shown on Fig. 3, where the space formed by the band *a* is sufficiently large to admit the hand of the wearer. The bracelet is then secured by closing the same, as shown on Fig. 4 and as previously described herein. In this case the extension *a*² of band *a* may be dispensed with, such extension being provided in other cases to prevent a soft material, such as that of which bags are made, from being caught within the elbow *g* when the lever *a* is being closed.

When used upon a hamper employed for carrying game and the like, the band *a* is slipped around the bar forming the edge of the lid and around the bar forming the top of the border of the hamper, when the fastener may be closed and sealed, as hereinbefore described.

40 What I claim, and desire to secure by Letters Patent of the United States, is—

1. A spring-band having a hooked lever jointed thereto and provided with a loop or loops to take with the hook of the lever and 45 a catch to engage with teeth formed on the end of the lever and a pad or boss to which

seal of wax may be affixed substantially as and for the purposes set forth herein.

2. A spring having a hooked lever jointed thereto and provided with a loop or loops to take with the hook of the lever and a catch to engage with teeth formed on the end of the lever and a pad or boss perforated with tapering holes whereby a seal of wax may be affixed and protected substantially as and for the purposes set forth herein.

3. A spring-band having a hooked lever jointed thereto and provided with a loop or loops to take with the hook of the lever and a catch to engage with teeth formed on the end of the lever and a pad or boss having a recess to protect the edges of the seal and perforated with tapering holes whereby a seal of wax may be affixed and protected substantially as and for the purposes set forth herein.

4. A spring-band having a hooked lever jointed thereto and provided with a loop or loops to take with the hook of the lever and a catch to engage with teeth formed on the end of the lever and a pad or boss to which a seal of wax may be affixed said spring-band being provided with holes for releasing the lever from the fastener, substantially as and for the purposes set forth herein.

5. In combination, the band having the elbow *g*, the lever pivoted to the elbow having one extremity pivotally engaging the band while its other extremity is toothed, and the catch on the band to be engaged by the tooth end of the lever, substantially as described.

6. In combination, the band, the hooked lever pivoted thereto intermediate of its length having one extremity hooked to pivotally engage the band while its other extremity is toothed and the engaging parts on the band at different points for receiving the hook and tooth.

GEORGE WILLIAM SHAILER.
